J. BERNSTEIN.

SOOT COLLECTOR.

APPLICATION FILED MAY 20, 1921.

1,412,334.

Patented Apr. 11, 1922.

UNITED STATES PATENT OFFICE.

JACOB BERNSTEIN, OF OMAHA, NEBRASKA.

SOOT COLLECTOR.

1,412,334.

Specification of Letters Patent. Patented Apr. 11, 1922.

Application filed May 20, 1921. Serial No. 471,279.

To all whom it may concern:

Be it known that I, JACOB BERNSTEIN, a citizen of the United States, and a resident of Omaha, in the county of Douglas and State of Nebraska, have invented a new and useful Improvement in Soot Collectors, of which the following is a full, clear, and exact description.

My invention relates to soot collecting devices, and it consists in the combinations, constructions and arrangements herein described and claimed.

An object of my invention is to provide a soot collector that is adapted for use in drawing soot from the smoke outlet of a heating apparatus and for conducting the soot to a desired place, as for instance, to a bag or other receptacle.

A further object of my invention is to provide a device of the character described that is capable of being moved readily from place to place for use in turn at widely separated points.

A further object of my invention is to provide a device of the character described that is relatively simple in construction and operation and not likely to get out of order easily.

A further object of my invention is to provide a soot collector that is thoroughly effective for the purpose intended and can be operated at a relatively low cost.

Other objects and advantages will appear in the following specification, and the novel features of the invention will be particularly pointed out in the appended claims.

My invention is illustrated in the accompanying drawings, forming part of this application, in which—

Figure 1 is a side elevation of the device, portions thereof being broken away and other portions being shown in section.

Figure 2 is an enlarged plan view of the device, portions thereof being broken away and other portions being shown in section,

Figure 3 is a sectional detail of a fragmentary portion of the device, and

Figure 4 is a detail of another fragmentary portion of the device.

In carrying out my invention, I make use of a vehicle which may be of any suitable type of construction and, in the drawings, is indicated generally at 1. Mounted upon the vehicle 1 is a power device 2 of ordinary construction. I prefer to use an internal combustion engine of an ordinary and well known type as the power mechanism in the

device. The internal combustion engine is secured by bolts 3 or other fastening means to the body of the vehicle. A fan 4 of the blower type is supported by a base 5 that is likewise secured to the vehicle body by suitable fastening means, such as the bolts 6. The fan 4 is driven by a belt and pulley connection indicated generally at 7 with the internal combustion engine 2. An intake or suction conduit 8 communicatively connects at one end with the fan 4 adjacent to the axis of the latter and is adapted for connection at its other end with a flexible tube 9. A delivery tube 10 leads from the periphery of the fan 4 and branches at 11 to provide two branch delivery tubes 12 and 13 respectively. The branch delivery tube 12 opens into a soot receiving member 14 through the side wall of the latter adjacent to its upper end, as best seen in Figure 3. The branch tube 13 likewise communicates with a similar soot receiving member 15 through the side wall of the latter adjacent to its upper end.

The soot receiving members 14 and 15 are substantially identical with one another in essential respects and each has the form of an inverted cone closed at its upper end except for a central opening 16 having a tubular extension 17 depending therefrom. Each soot collecting cone is provided with a discharge orifice 18 at its lower end and a suitable receptacle 19 which may be a bag, is removably secured at 20 at the lower end of each cone to receive the soot passing through the discharge orifice 18. Arranged to enter the opening 16 to depend within each cone is the tubular portion 21 of a header 22 which is enlarged exteriorly of the cone so that the walls thereof are inclined outwardly, as shown. The header 22 is provided with an upper end wall 23 which has a central opening 24. An up-

standing tubular member 25 from the opening 24 is integral with the wall 23. An intake tube 26 is arranged to enter the tubular member 25 to depend through the opening 24 into the header 22 to a point slightly below the level of the upper end of the cone. A screen supporting frame 27 has a tubular stem 28 disposed in the upper end of the intake tube 26 and supported by the latter. The screen supporting frame 27 is covered by a screen 28' of suitable mesh and is provided with radially extending brace rods 29. Certain of the brace rods 29 connect with the tubular stem 28, while others are

stayed by a tie member 30. The stem 28 is fashioned with an inwardly extending lug 31 constituting a bearing for a crank 32. A brush 33 is carried by the crank arm 32 in position to engage the inner wall of the screen 28' when the crank is rotated. The screen 28' may consist of a suitable fabric, preferably a heavy cloth, and be renewed when worn or damaged in service. A return conduit 34 is provided for each head 22 and connects with the latter adjacent to its upper end. The conduits 34 unite at 35 to provide a main return conduit 36 that communicates with the fan 4 adjacent to the axis of the latter.

From the foregoing description of the various parts of the device, the operation thereof may be readily understood. The flexible tube 9 may be formed of sections to provide any suitable length and the end thereof is connected to the smoke outlet of the heating apparatus from which the soot is to be drawn. The fan 4 is then operated and soot is drawn through the intake conduit 8 and blown therefrom through the delivery tube 10 and, through the branch delivery tubes 12 and 13 into the soot receiving cones 14 and 15. It is to be observed that the air with the entrained soot forced along the delivery tube 10 enters each cone through its side wall at the upper end of the latter and the mingled soot and air will pass in spiral convolutions of decreasing diameter downwardly through the soot receiving cone, thereby creating a partial vacuum at the center of each cone. The soot will be discharged through the discharge orifice 8 into the receptacles 19. The return tube 36 also communicates with the fan 4 adjacent to the axis of the latter and the operation of the fan will cause a suction on the head 22 which will tend to draw air upwardly from the center of the cone, thereby drawing practically all air from the cone into the branch return tubes 34, while practically all of the soot passes into the receptacles 19. In the event any of the finer soot passes upwardly with the air drawn into the tubes 34, it may pass along the latter to the fan 4 and be forced through the delivery tube 10 again. Any soot entering the tubular intake member 26 will be caught by the screen 28' and may be dislodged therefrom by operating the crank 32 either before or after the screen frame has been removed from the header 22. It will thus be obvious that practically all the soot drawn from the flue is collected. The device may be moved readily from place to place and is ready for operation instantly. The soot receiving cones 14 and 15 are supported on the vehicle body by suitable fastening means, such as the brackets 37.

I claim:

1. In a device of the character described,

a receptacle having the general shape of an inverted cone formed with a wall at its upper end, said receptacle being provided with a discharge opening at its smaller lower end, with an intake port opening through its side wall adjacent to the upper end thereof, and with a central opening through its upper end wall, a header having a tubular portion fitting the central opening of said upper end wall and depending within said receptacle, said header having a portion of larger cross-sectional area positioned above the upper end wall of the receptacle and being provided with an air return port opening through its side wall adjacent to its upper end and with an axial opening through its upper end wall, a frame having a tubular portion fitting the axial opening in the upper end wall of the header and depending within the latter, a foraminous flexible member arranged to cover the frame, movable means supported within the frame and operable exteriorly of the frame at will for contacting the foraminous member to dislodge dust therefrom, whereby such dust will fall into said first named receptacle, and means connected with said intake port and with said air return port for blowing commingled air and dust through the former and for causing a suction on the latter.

2. In a device of the character described, a receptacle having the general shape of an inverted cone formed with a wall at its upper end, said receptacle being provided with a discharge opening at its smaller lower end, with an intake port opening through its side wall adjacent to the upper end thereof, and with a central opening through its upper end wall, a header having a tubular portion fitting the central opening of said upper end wall and depending within said receptacle, said header having a portion of larger cross-sectional area positioned above the upper end wall of the receptacle and being provided with an air return port opening through its side wall adjacent to its upper end and with an axial opening through its upper end wall, a frame having a tubular portion fitting the axial opening in the upper end wall of the header and depending within the latter slightly below the upper end of the first named receptacle, a foraminous flexible member arranged to cover the frame, movable means supported within the frame and operable exteriorly of the frame at will for contacting the foraminous member to dislodge dust therefrom, whereby such dust will fall into said first named receptacle, and means connected with said intake port and with said air return port for blowing commingled air and dust through the former and for causing a suction on the latter.

JACOB BERNSTEIN.
